UNITED STATES PATENT OFFICE.

BERTHOLD A. BAER, OF NEW YORK, N. Y., ASSIGNOR TO FRANK E. CAMPBELL, OF NEW YORK, N. Y.

SEALING MEANS FOR BURIAL-CASKETS.

1,371,720.

Specification of Letters Patent. Patented Mar. 15, 1921.

Application filed October 29, 1919. Serial No. 334,285.

To all whom it may concern:

Be it known that I, BERTHOLD A. BAER, a citizen of the United States, and resident of the borough of Manhattan, in the city and State of New York, have invented a new and useful Improvement in Sealing Means for Burial-Caskets, of which the following is a specification.

This invention relates to improvements in sealing means for burial caskets and has for its object to provide a closure which will be automatically locked and hermetically sealed.

Another object is to provide a structure which will prevent the surplus sealing compound from flowing into the interior of the casket.

Another object is to provide means whereby the sealing compound may flow toward the outside of the closure, where the excess compound may be collected and readily removed without affecting the artistic appearance of the casket.

A still further object is to provide certain improvements in the form, construction and arrangement of the parts whereby the above named and other objects may be effectively attained.

A practical embodiment of my invention is represented in the accompanying drawing, in which—

Figure 1 represents a side elevation of a burial casket having my improved sealing means applied thereto.

Fig. 2 represents an enlarged detail section showing a portion of the casket and its cover in position to be applied thereto.

Fig. 3 represents a similar view with the cover and body locked and hermetically sealed, and

Fig. 4 represents a modified form of casket having its sealing member secured to the wood lining.

In the form shown in Figs. 1 to 3 inclusive, the body portion of the casket is denoted by 1, the molding by 2 and the inwardly disposed rim by 3, all of which are formed integral.

The rim 3 is provided in its upper face with a continuous groove 4 extending around the sides and ends of the body, the outer wall 5 of which groove is undercut. The inner wall 6 of the groove projects upwardly above the upper face of the rim to

form a seat 7 for the cover 8. The cover 8 is provided with a continuous depending flange 9, the outer wall 10 of which is inclined inwardly and upwardly and approximately parallel to the wall 5 of the rim 3, so that when the cover is placed in position upon the rim the flange 9 will enter the groove 4, leaving the lower edge of the inclined wall 10 spaced a sufficient distance to pass the upper edge of the wall 5 of the rim.

A sealing compound 11 is inserted in the groove 4, prior to the positioning of the cover, into which compound the flange 9 is securely embedded. To prevent the compound from being forced into the interior of the casket when displaced by the flange, I locate thin strips 12 of flexible material, such as sheet metal, along the inner wall 6 of the groove 4, in position to be engaged by the cover, so that as the cover is brought downwardly toward the rim the upper edge of the strips will be curled over making a tight joint at the point where the strips engage the flange, and thus prevent the compound from flowing toward or over the seat 7, as shown in Fig. 3. To allow the excess compound to flow freely away from the strips, I provide the flange 9 with a series of arched passages 13, in its lower edge, through which passages the compound may pass. The surplus compound passing outwardly from the groove will be forced through an open joint 14 formed between the opposed surfaces of the cover and rim, which joint is concealed by a peripheral bead 15 depending from the cover.

In the form shown in Fig. 4, the body portion 16 is formed of sheet metal and reinforced by a wood lining 17. A rim 18 is secured to the body and lining by means of depending lugs 19 and pins or rivets 20 engaging the body, lining and lugs. A molding 21 is fastened to the body and rim by soldering or any other well known and approved means. The rim is provided with a continuous groove 22 having its outer wall 23 undercut and its inner wall 24 extended upwardly above the upper surface of the rim. Flexible strips 25 are located adjacent the wall 24 and are adapted to be engaged by the cover 26 and be curled over toward the continuous depending flange 27. The flange 27 is provided along its lower edge

with arched passages 28 through which the compound 29 flows. The compound passing outwardly from the groove 22 will be caused to exude through the joint 30 between the 5 opposed surfaces of the rim and cover. This joint is concealed by a peripheral bead 31 depending from the cover 26.

It will be understood that the sealing compound used in the grooves is inserted 10 prior to applying the cover and substantially of a semi-plastic state so that it will flow readily and be easily displaced to fill the spaces between the cover and the rim, thereby hermetically sealing the joint as 15 soon as the compound sets and hardens.

It is obvious that various changes may be resorted to in the form, construction and arrangement of the parts, without departing from the spirit and scope of my invention; 20 hence I do not intend to be limited to the details herein shown and described except as they may be specifically included in the claims.

What I claim is:

25 1. A burial casket comprising a body having a continuous undercut groove in its upper surface, a cover provided with a continuous depending flange adapted to enter said groove, a sealing compound in the 30 groove arranged to embed said flange and a flexible metallic means vertically disposed in the groove and arranged to coact with the cover for preventing the compound from entering the interior of the body.

35 2. A burial casket comprising a body having a continuous undercut groove in its upper surface, a cover provided with a continuous depending flange adapted to enter said groove, a sealing compound in the 40 groove arranged to embed said flange and a separate flexible metallic means vertically disposed in the groove and arranged to coact with the cover for preventing the compound from entering the interior of the body.

45 3. A burial casket comprising a body having a continuous undercut groove in its upper surface, a cover provided with a continuous depending flange adapted to enter said groove, a sealing compound in the 50 groove arranged to embed said flange, passages in the lower edge of the flange for the transit of the sealing compound, and means vertically disposed in the groove and arranged to coact with the cover for preventing the compound from entering the interior of the body.

55 4. A burial casket comprising a body having a continuous undercut groove in its upper surface, a cover provided with a continuous 60 depending flange adapted to enter said groove, a sealing compound in the groove arranged to embed said flange, arched passages in the lower edge of the flange for the transit of the sealing compound, and means vertically disposed in the groove and 65

arranged to coact with the cover for preventing the compound from entering the interior of the body.

5. A burial casket comprising a body having a rim, a continuous undercut groove in 70 said rim, a cover provided with a continuous depending flange adapted to enter said groove, a sealing compound in the groove arranged to embed said flange, passages in the lower edge of the flange for the transit 75 of the sealing compound, and means vertically disposed in the groove and arranged to coact with the cover for preventing the compound from entering the interior of the body. 80

6. A burial casket comprising a body having a rim, a continuous undercut groove in said rim, a cover provided with a continuous depending flange adapted to enter said groove, said cover being seated on the inner 85 wall of the groove and spaced from the top of the outer wall, a sealing compound in the groove arranged to embed said flange, and means vertically disposed in the groove and arranged to coact with the cover for 90 preventing the compound from entering the body.

7. A burial casket comprising a body having a rim, a continuous undercut groove in said rim, a cover provided with a continuous 95 depending flange adapted to enter said groove, said cover being seated on the inner wall of the groove and spaced from the top of the outer wall, a sealing compound in the groove arranged to embed said flange, passages in the lower edge of the flange for the transit of the sealing compound and means vertically disposed in the groove and arranged to coact with the cover for preventing the compound from entering the interior 100 of the body. 105

8. A burial casket comprising a body having a rim, a continuous undercut groove in said rim, a cover provided with a continuous 110 depending flange adapted to enter said groove, the inner wall of the groove projecting upwardly beyond the outer wall to form a seat for said cover, a sealing compound in the groove arranged to embed said flange, and means vertically disposed in the groove 115 adjacent said inner wall arranged to coact with the cover for preventing the compound from entering the interior of the body.

9. A burial casket comprising a body having a rim, a continuous undercut groove in 120 said rim, a cover provided with a continuous depending flange adapted to enter said groove, the inner wall of the groove projecting upwardly beyond the outer wall to form a seat for said cover, a sealing compound in 125 the groove arranged to embed said flange, passages in the lower edge of the flange for the transit of the sealing compound and means vertically disposed in the groove adjacent said inner wall and arranged to co- 130

act with the cover for preventing the compound from entering the interior of the body.

10. A burial casket comprising a body having a rim, a continuous undercut groove in said rim, a cover provided with a continuous depending flange adapted to enter said groove, the inner wall of the groove projecting upwardly beyond the outer wall to form a seat for said cover and an open joint between the opposed surfaces of the cover and rim exterior to said flange, a sealing compound in the groove arranged to embed the flange, passages in the flange for the transit of the sealing compound, means adjacent 15 said inner wall coacting with the cover for preventing the compound from entering the interior of the body, and means on the cover for concealing said joint.

11. A burial casket comprising a body having a rim, a continuous undercut groove in

said rim, a cover provided with a continuous depending flange adapted to enter said groove, the inner wall of the groove projecting upwardly beyond the outer wall to form a seat for said cover and an open joint between the opposed surfaces of the cover and rim exterior to said flange, a sealing compound in the groove arranged to embed the flange, passages in the flange for the transit of the sealing compound, means adjacent 25 said inner wall coacting with the cover for preventing the compound from entering the interior of the body, and a peripheral bead depending from the cover 30 for concealing the joint.

In testimony, that I claim the foregoing as my invention, I have signed my name this 23rd day of October, 1919.

BERTHOLD A. BAER.
